(57)

CLAIM

The ornamental design for a pistol compensator, as shown and described.

DESCRIPTION

FIG. 1 is a right front upper perspective view of a pistol compensator;

FIG. 2 is a left rear lower perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is an upper plan view thereof; and,

FIG. 8 is a lower plan view thereof.

The broken lines in the drawings are for the purpose of illustrating portions of the pistol compensator that form no part of the claimed design.

1 Claim, 2 Drawing Sheets
